UNITED STATES PATENT OFFICE

LUTHER E. SIMMONS, OF BANCROFT, WEST VIRGINIA

PERMUTATION LOCK

Application filed June 30, 1928. Serial No. 289,494.

The present invention has reference to an improved permutation lock of the mortise type, such as is especially adapted for swinging doors.

5 Briefly described, the lock comprises a casing designed to fit in a mortised opening, in the door. This casing contains a spring projected latch, a slideable tumbler plate having operating connection with the latch and constructed to accommodate a multiple arrangement of rotary tumblers.

The tumblers are controlled by individual indicator knobs cooperating with graduated dials. The tumbler plate is operated by a handle located on the outside of the door. 15 The sliding latch is operated from the outside by the tumbler plate and from the inside by an independently operable handle.

One feature of construction is the novel 20 sliding tumbler plate, which is arranged within the casing and has pin and slot connection with the latch, whereby to permit the latch to be operated from the inside of the door independently of the tumbler plate. The 25 tumbler plate is also characterized at its inner end with lateral abutments with which the oscillatory roll back has operating connection.

The multiple rotary tumbler arrangement 30 is also regarded as a novel improvement in the art, in that the operation of the tumblers may be accurately gauged by indicator knobs cooperating with graduations on the graduated dial, this structure being advantageous in 35 that it individualizes the lock and prevents opening of the lock by unauthorized persons.

An equally important feature is the inside 40 slidably mounted handle which has operating connection with the latch and which is constructed for cooperation with a pivotally mounted retainer, functioning to prevent movement of the handle when desired.

In carrying out this invention, I have endeavored to provide a mechanical achievement 45 which is characterized by dependability, efficient performance, selectivity in operation and other features which permit the structure to fulfill the requirements of a lock of this class.

50 In the drawings:

Figure 1 is an elevational view, showing the lock installed in a door and observing the structure from the outside.

Figure 2 is a view similar to Figure 1, reviewing the structure from the inside. 55

Figure 3 is an edge view of the door, showing the projecting parts of the lock.

Figure 4 is an elevational view of the lock casing removed from the door.

Figure 5 is a view based on Figure 4, observing the opposite side and showing the cover plate removed to expose the internal mechanism. 60

Figure 6 is a horizontal sectional view through the lock installed. 65

Figure 7 is a transverse or vertical sectional view.

Figure 8 is a fragmentary view, based on Figure 5, with the slideable tumbler plate removed. 70

Figure 9 is an inside perspective view of the tumbler plate per se.

Figure 10 is a perspective view of one of the tumblers.

Figure 11 is a perspective view of the spindle. 75

Figure 12 is a perspective view of a keeper plate, such as is mounted upon the door frame.

As before intimated, the structure embodies a casing which in this instance is substantially 80 rectangular in configuration and hollow in construction. The body portion 13 of the casing is seen better in Figure 5, wherein it will be observed that it is provided with the usual end flanges 14, which are screwed or otherwise fastened to the edge of the door 15 as shown in Figure 3. Located in this portion of the casing is the slideable latch 16, (see Figure 8) which is normally forced outwardly under the action of the spring 17, suitably 85 anchored in the casing. The latch has an outstanding pin 18 which serves a purpose to be hereinafter described and it includes the usual bevelled projecting nose 19.

Attention is now invited to Figure 5 where- 90 in it will be observed that the reference character 20 designates the slideable tumbler plate. This is disposed in sliding contact with the bolt 16 and is provided with an elongated slot 20^a, at its forward end through which the 95 100

pin 18 projects. The outer surface of this tumbler plate is provided with circular sockets or depressions 21 which are in communication with each other as at 22. The outer depression 5 also communicates with a groove 23. The inner end of the tumbler plate is bifurcated and the furcations are provided with right angularly directed extensions or fingers 24, (see Figure 9), which cooperate with the oscillatory roll back 25, (see Figure 5). The body portion of the roll back is located 10 between the furcations and carries oppositely projecting actuators 27, which engage the fingers 24. The roll back is of course, mounted for oscillation in the casing, and in this instance is formed with a polygonal opening for 15 reception of the correspondingly shaped spindle 28, carried by the shank 29 of the outside handle 30, (see Figure 7). Thus, the handle 20 can be turned in either direction to rock the roll back and in turn to slide the tumbler plate inwardly. Since the pin 18 is located in the forward end of the slot 20^a, it is obvious 25 that this motion will withdraw the latch 16. The latch, however, has independent sliding motion from the inside of the door. The inside operation is accomplished through the use of a substantially U-shaped handle 31, which is arranged as shown in Figure 6. As 30 is apparent here, the arm portions of the handle are provided with outwardly extending feet 32, in sliding contact spacing plate 33. The spacing plate is slotted and a handle 31 carries small headed fastenings 34 movable 35 in the slot. The forward foot 32 is provided with a socket receiving a right angularly projecting stud 35, on one side of the latch, it being noted that in this connection, the body 13 is formed with openings to accommodate 40 the projecting portions on the latch. It is therefore obvious that by grasping the handle 31 and sliding it inwardly, the latch will be withdrawn and moved independently of the tumbler plate 20. It is possible, however, 45 to retain the handle 31 against movement through the utilization of a small pivoted retainer 36, mounted on the spacing plate 33 and occupying the position as better shown in Figure 2. This retainer has its free end portion 50 so shaped as to engage an adjacent arm of the handle 31, as is shown in Figure 2, and when thus positioned, the handle cannot be moved. This permits the door to be locked from the inside. Attention is now invited to 55 the construction and arrangement of the multiple rotary tumbler assembly which is employed to lock the tumbler plate from the outside but to permit it to be released for operation by the handle 30 when so desired.

60 I employ two tumblers 37 of the construction shown in Figure 10. As seen here, the head of the tumbler is of general T-shaped construction as indicated at 38 and the stem 39 is of polygonal cross sectional shape. 65 Thus, the head portion of the tumbler is

adapted for reception in the aforesaid depression 21 in the tumbler plate. It is obvious, however, that when the tumblers are in the position seen in Figure 5, the tumbler plate 20 cannot be manipulated. However, by turning the tumblers so that the leg portions register with the grooves 22 and 23 respectively, it is obvious that the tumbler plate can then be manipulated by turning the handle 30 in either direction. 70

In accordance with the invention, these tumblers are cooperable with graduated dials 40 on the outside facing plate 41, as seen in Figure 1. It will be noted also that the stem portion 39 of the tumblers extend out through 75 openings in the casing cover plate 42, and two additional openings in the facing plate 41. The extended portions carry knurled finger grips or knobs 43, (see Figures 3 and 6). Then, as better shown in Figure 1, each knob 80 is provided with a pointer 44, adapted to operate with the graduations on the dial. The arrangement is such that the pointer must be opposite a predetermined graduation on the dial before the tumbler plate 20 is released. 90

The final detail to be mentioned is the keeper plate 45, seen in Figure 12. This, however, is of ordinary construction, and as usual is mounted on the door frame 46. This is of no 95 consequence, in so far as the novelty of this invention is concerned. 100

I claim:

1. A lock of the class described comprising 105 a casing, a latch slideable in the casing, an inside handle for operating the latch, a sliding plate in the casing in slideable contact with the latch, an oscillatory roll back in the casing having an operating connection with the sliding plate, and an outside operating handle for said roll back, said sliding plate having a depression, a tumbler located in the depression, and operating means for the tumbler. 110

2. A permutation lock of the mortise type 115 comprising a hollow casing, a spring protected latch slideably mounted in the casing, an inside handle having operating connection with said latch, a pivoted retainer for said handle, a tumbler plate slideably mounted in the casing and in sliding contact with the latch, an outside handle having operating connection with said tumbler plate, said tumbler plate being formed in its outer surface with a depression, a rotary T-shaped tumbler 120 located in the depression and provided with outstanding inturned stem, and a knob carried by the stem. 125

3. A permutation lock of the mortise type comprising a hollow casing, a spring protected latch slideably mounted in the casing, an inside handle having operating connection with said latch, a pivoted retainer for said handle, a tumbler plate slideably mounted in the casing and in sliding contact with the 130

- latch, an outside handle having operating connection with said tumbler plate, said tumbler plate being formed in its outer surface with a depression, a rotary T-shaped 5 tumbler located in the depression and provided with outstanding inturned stem, and a knob carried by the stem, together with an outside facing plate disposed against the outer surface of said casing and interposed between 10 said outside handle and knob, said facing plate being provided with a graduated dial, and said knob having a pointer cooperating with said dial to indicate the position of the tumbler.
- 15 4. A permutation lock of the mortise type comprising a hollow casing, a spring projected latch slidably mounted in the casing, an inside facing plate for the casing, a substantially U-shaped handle slidably mounted 20 on said facing plate and having operating connection with said latch, a pivoted retainer carried by said inside facing plate and engageable with said handle, and exteriorly disposed operating means for said latch.
- 25 5. A permutation lock of the mortise type comprising a hollow casing, a spring projected latch slidably mounted in the casing, an inside facing plate for the casing, a substantially U-shaped handle slidably mounted 30 on said facing plate and having operating connection with said latch, a pivoted retainer carried by said inside facing plate and engageable with said handle, and exteriorly disposed operating means for said latch, said 35 exteriorly disposed means having pin and slot connection with the latch whereby to permit the latch to be independently operated from the inside by the inside handle.

In testimony whereof I affix my signature.
40 LUTHER E. SIMMONS.
